APPARATUS FOR SINTERING ROASTED MATERIALS

Application filed May 5, 1931, Serial No. 535,204, and in Germany April 12, 1930.

Various systems have hitherto been successfully employed for roasting the refined spar produced by the dressing of spar. Most of these systems were, however, little suited for sintering also the roasted material. Two systems which have obtained importance in practice but cannot be considered advantageous owing to their wastefulness are herein-after mentioned. According to one of these, 5 a cylindrical furnace, which was journalled nearly horizontally, was set in continuous rotation so that the refined spar passed slowly through the furnace. Firing was by means of coal dust which was blown in and caused 10 the material being treated to sinter. The furnace however had to be shut down every third day and the opening to be freed from the fired material. There must also be mentioned a furnace system in which a crucible 15 is heated with coke. The output is small and the consumption of coke very high.

Now the subject matter of the present invention is an apparatus for sintering refined spar or the like by which it is possible in a 20 particularly advantageous manner completely to sinter roasted refined spar or the like in the red hot condition, and thereby obtain by the sintering, which takes place in direct conjunction with the roasting of the material, a 25 charge material in the form of coarse pieces which is pre-eminently suitable for smelting. The furnace by which this object is effected is adaptable to almost any existing roasting system and can be fitted in a particularly ad- 30 vantageous manner to roasting furnaces having several stages. The material to be sintered can be roasted in the upper stages and caused to sinter in the chamber in accordance 35 with the invention. How the roasting pro- 40 cess is not of importance in this connection.

In this apparatus the previously roasted refined spar or the like which is preferably still in the red hot condition is directly delivered on to a layer of solid glowing combustible material, for example coke, and additional heating gas is conducted over its surface.

The furnace for carrying out this process consists of a chamber with a removable bot- 45 tom constructed in one or more parts on which

the solid combustible material and afterwards the charge to be sintered is placed. In order to ignite the fuel there are arranged in the bottom, in accordance with the invention, 55 passages, for example in the form of nozzles, which conduct air to the fuel. When the fuel has been ignited with the aid of the heat radiated by the heating gases passed through the furnace, the roasted refined spar or the like is placed on it and is caused to sinter by 60 the heating gases which now flow over the refined spar.

The placing of the solid fuel on the bottom of the furnace or on the bottom portions as well as the removal of the sintered charge 65 takes place automatically, in accordance with the invention, on displacing the furnace parts, since the bottom parts are lowered at the beginning of their entry into the furnace and are raised against a scraping surface on 70 the beginning of their removal from the furnace. This automatic lowering and raising of the bottom parts can be effected in accordance with the invention by pivoting each part of the bottom of the furnace through 75 the agency of levers to carriage axles, so that on entering into and on coming out from the furnace they swing about the axles and are thereby lowered or raised until a draw-bar or the like, which engages the axles, abuts by 80 means of projections with which it is provided against a stop fixed to the bottom part.

A constructional embodiment of the invention is illustrated by way of example in the accompanying drawing, in which

Fig. 1 is a longitudinal section and

Fig. 2 a cross-section through the sintering furnace, while

Fig. 3 shows a longitudinal section through a cleaning tube and a nozzle box.

Referring to the drawing, the sintering furnace consists of a chamber which is swept by the heating gases which pass through laterally arranged firing passages 3. The bottom of the chamber is closed by the two sintering surfaces 1 which form the bottom of the furnace. The consist of fire-resistant bricks held together by an iron frame. Several nozzle boxes 4 are inlet in the upper surface. These are long four-sided boxes in 100

the top of which nozzle holes are bored. In order to remove any dust which may fall into it from the box 4 there is provided, in accordance with the invention, at the end of 5 each box a downwardly directed cleaning tube 5 having a ball valve 7. When the pressure is increased the ball opens the valve whereas at the normal operating pressure a spring presses the ball upwards. Each sintering surface 1 rests on a travelling frame having two upper and two lower axles. The upper axles are pivotally connected by arms 2 with the two lower axles. According to 10 the position of these arms 2, the surface 1 lies higher or lower. If, for example the right-hand carriage frame is drawn out of the furnace by means of the draw-bar 8 the bottom part 1, which otherwise maintains its position, is at first raised, owing to the fact that 15 the lower axles and wheels move to the right until the stop 9 of draw-bar or rod 8 is applied against the stop 9' which is rigidly connected to part 1. Only then does the whole furnace part move outwards, as is illustrated 20 on the left-hand side of the Fig. 1. The reverse procedure takes place on returning the parts into the furnace.

In order that every part of the sintering coke may come into contact with the air from 30 the nozzles the surface is preferably grooved. On closing the bottom, i. e. on moving inwards the lowered bottom portions 1, the laterally arranged coke containers 6 deliver the necessary coke to the lowered surfaces.

35 The delivery of the roasted material from the roasting furnace into the sintering furnace can take place through openings 13 provided in an arched roof of the sintering furnace. A slider consisting of a vertical plate 40 10 and several runners 11 is moved backwards and forwards by the air cylinder 12 and thereby presses down the material in the roasting furnace on the roof of the sintering furnace. In the drawing, two positions of the slide are 45 illustrated, the right-hand position shows the extreme position of the slide in this direction in which the plate 10 simultaneously serves the purpose of a closure to the outside. The next higher stage of the roasting furnace 50 can be constructed in a similar manner and be provided with a slide, in which case however the opening and the bottom preferably alternate in the vertical plane and the slides are movable alternately from left or right.

55 As set forth in the specification, the fuel is ignited before the introduction of the roasted material by the heating gas passing from the lateral furnace 3. The material to be sintered is distributed in that the slide 10 shoves the roasted material aside, so that it falls through the slots 13. The uniformity of the distribution on the portable bottom 1 is entirely sufficient and, as found by experience, these slots should not be too wide. 60 65 When the carriage is rolled out laterally bot-

tom 1 is raised, so that the sintered material is stripped off by the bars 15 and falls through of its own weight. The air nozzles are connected with a compressed air pipe by the passage 14 shown at the outside, and thus supplied with air. As a result of a temporary increase of the air pressure in the nozzle housing the ball 16 closing the passage 7 is forced back against the action of the spring 17, and the orifice thus opened for the discharge of the collected dust. When the carriages are rolled out there is no longer any collected material on the furnace cover perforated by the slots 13 which can drop down. The carriages are drawn out only so far that the lower openings of the lateral fuel reservoirs 6 remain closed by the bottom 1.

I claim:—

1. Sintering furnace comprising a furnace chamber, means for gas-firing said furnace chamber, a laterally removable grate forming the bottom of said chamber on which first a layer of solid fuel and upon this a layer of the material to be sintered is deposited and said grate being provided with passages for conducting air to the fuel. 85

2. Sintering furnace comprising a furnace chamber, a laterally removable grate, which forms the bottom of said chamber and consists of separately movable grate portions, on which first a layer of solid fuel and upon this a layer of the material to be sintered is deposited, and said grate being provided with passages for conducting air to the fuel. 95

3. Sintering furnace comprising a furnace chamber, means for gas-firing said furnace chamber, a laterally removable grate, which forms the bottom of said chamber and consists of separately movable grate portions, on which first a layer of solid fuel and upon this a layer of the material to be sintered is deposited, and said grate being provided with passages for conducting air to the fuel. 100

4. Sintering furnace comprising a furnace chamber, means for gas-firing said furnace chamber, a laterally removable grate, which forms the bottom of said chamber on which first a layer of solid fuel and upon this a layer of the material to be sintered is deposited, said grate being provided with passages for conducting air to the fuel, cleaning tubes connected to said passages and valves in said cleaning tubes for closing same to the atmosphere. 115

5. Sintering furnace comprising a furnace chamber, means for gas firing said furnace chamber, a laterally removable grate, which forms the bottom of said chamber on which solid fuel and charge to be sintered are deposited, the latter upon the former, said grate being provided with passages for conducting air to the fuel, scraping means located above said grate and means for automatically raising said grate when it is with- 120 125 130

drawn from the furnace so that said scraping means remove the sintered charge.

6. Sintering furnace comprising a furnace chamber, means for gas firing said furnace chamber, a laterally removable grate which forms the bottom of said chamber on which solid fuel and the charge to be sintered are deposited the latter upon the former, said grate being provided with passages for conducting air to the fuel, scraping means located above said grate, means for automatically raising said grate when it is withdrawn from the furnace so that said scraping means remove the sintered charge, and means for automatically lowering said grate away from said scraping means when it is introduced into the furnace with the charge of solid fuel upon it.

7. Sintering furnace comprising a furnace chamber, means for gas-firing said furnace chamber, a laterally removable grate, which forms the bottom of said chamber and consists of separately movable grate portions on which the fuel and charge to be sintered are deposited, the latter upon the former, said grate being provided with passages for conducting air to the fuel, scraping means located above said grate, means for automatically raising said grate when it is withdrawn from the furnace so that said scraping means remove the sintered charge.

8. Sintering furnace comprising a furnace chamber, means for gas-firing said furnace chamber, a laterally removable grate which forms the bottom of said chamber, which consists of separately movable grate portions, on which solid fuel and the charge to be sintered are deposited, the latter upon the former, said grate being provided with passages for conducting air to the fuel, scraping means located above said grate, means for automatically raising said grate when it is withdrawn from the furnace so that said scraping means remove the sintered charge, and means for automatically lowering said grate away from said scraping means when it is introduced into the furnace with the charge of solid fuel upon it.

9. Sintering furnace comprising a furnace chamber, means for gas-firing said furnace chamber, a laterally removable grate which forms the bottom of said furnace chamber and consists of separately movable grate portions on which first a layer of solid fuel and upon this a layer of the material to be sintered is placed, wheel-axles connected by links to said grate portions so that said grate portions can swing about said axles, stops secured on the grate portions, draw-bars connected to said axles, and projections on said draw-bars adapted to engage said stops and thereby limit the extent to which said grate portions can swing.

10. Process for sintering roasted materials which comprises providing a layer of

solid fuel, passing heated gases thereover, thereby igniting said fuel, charging a layer of the material to be sintered on the fuel and passing heating gases over its surface.

In testimony whereof I affix my signature. ⁷⁰
